REFRIGERATION

Albert R. Thomas, Evansville, Ind., assignor to
Servel, Inc., New York, N. Y., a corporation of
Delaware

Application August 3, 1940, Serial No. 350,239

10 Claims. (Cl. 62—5)

This invention relates to refrigeration, and more particularly to refrigeration systems of the type operated by heat and with which may be associated a heating system.

In application Serial No. 239,762 of A. R. Thomas and P. P. Anderson, Jr., filed November 10, 1938, it has already been proposed to provide an absorption refrigeration system having a generator or vapor expeller provided with a steam chamber to which steam is supplied to cause expulsion of refrigerant vapor from absorption liquid and also effect lifting of liquid to a higher level by vapor-lift action. The steam for effecting heating of the generator may be supplied from a steam boiler which operates substantially at atmospheric pressure, the steam chamber associated with the generator having a vent to permit steam to flow therefrom into the atmosphere.

The steam boiler also may be arranged to effect heating of a heating element or radiator of a heating system, the radiator also having a vent to permit steam to flow therefrom into the atmosphere. The cooling element of the refrigeration system and the heating element of the heating system may be arranged in a duct through which air passes to an enclosure, and suitable valves may be provided so that the steam from the boiler either effects heating of the generator to cause a cooling effect to be produced by the cooling element, or heating of the radiator to cause a heating effect to be produced by the heating element.

It is an object of this invention to provide an improvement for controlling the heat supply to the steam boiler, so that the supply of steam to the generator of the refrigeration system or to the heating element of the heating system is reduced when steam passes into the atmosphere through the vents provided in the generator steam chamber and heating element. This is preferably accomplished by joining the vents of the generator steam chamber and heating element to provide a single common vent, and controlling the flow of fuel to a burner associated with the steam boiler responsive to the temperature condition in the common vent. When provision is made for returning steam condensate to the boiler, the control provided prevents excessive loss of water from the boiler, so that the necessity of a float valve for make-up boiler water is avoided. Further, the single control provided takes the place of many controls that would otherwise be necessary to insure safe operation of the refrigeration system and also of the

heating system. The provision of a single control to take the place of many controls is possible because numerous adverse operating conditions that may occur are felt at the vent through which steam can pass into the atmosphere. For example, the cessation of cooling water to the absorber and condenser of the refrigeration system causes rise in temperature of these parts and also rise in temperature of the generator, so that steam will pass through the vent into the atmosphere. In the refrigeration system a high concentration of lithium chloride or similar salt solution is employed which is close to the solidifying point, and under adverse conditions such as a quantity of salt may precipitate that the passages in the absorption liquid circuit are closed and blocked. Blocking or plugging of the absorption liquid circuit causes the temperature of the generator to rise, so that steam will pass through the vent into the atmosphere. Also, when the blower in the duct system stops and there is loss of air circulation during a period when steam is being supplied to the heating element or radiator, the loss of load on the element causes steam to flow through the vent into the atmosphere. It will be evident, therefore, that safe operation of the refrigeration system and heating system can be insured by controlling the heat supply to the steam boiler responsive to flow of steam through the common vent to the atmosphere.

The invention, together with the above and other objects and advantages thereof, will be better understood from the following description taken in conjunction with the accompanying drawing forming a part of this specification, and of which:

Fig. 1 is a view more or less diagrammatically illustrating a refrigeration system and heating system provided with a control embodying the invention; and

Fig. 2 is a fragmentary view diagrammatically illustrating another embodiment of the invention.

Referring to the drawing, the present improvement is shown in connection with a two-pressure absorption refrigeration system like that described in the aforementioned Thomas and Anderson application. A system of this type operates at low pressures and includes a generator or expeller 10, a condenser 11, an evaporator 12, and an absorber 14 which are interconnected in such a manner that the pressure differential in the system is maintained by liquid columns.

The disclosure in the aforementioned Thomas and Anderson application may be considered as being incorporated in this application, and, if desired, reference may be made thereto for a detailed description of the refrigeration system. The generator 10 includes an outer shell 15 within which are disposed a plurality of riser tubes 16 having the lower ends thereof communicating with a space 17 and the upper ends thereof extending into a vessel 18. The space 19 within shell 15 and about the tubes 16 forms a steam chamber to which steam is supplied through a conduit 20 forming boiler 21.

The boiler 21 is provided with a fire or heating tube 22 into the lower end of which is adapted to project the flame produced by a burner 23. A combustible gas is delivered from a source of supply through a conduit 24, a control device 25 to be described presently, and conduit 26 to the burner 23. While only a single heating tube and burner are illustrated, a number of heating tubes and burners may be employed with the upper end of each tube connected to a flue or riser 27. The water in boiler 21 is heated by the hot gases passing through the heating tubes 22, thereby producing steam which flows through conduit 28 to generator 10. A suitable hand controlled valve 29 is provided in conduit 20 to obtain manual control of the steam flow to the generator.

The space 19 provides for full length heating of riser tubes 16 by the steam, and a vent 28 is provided at the upper end of shell 15 through which steam can flow into the atmosphere, as will be described presently. Condensate formed in steam chamber 19 flows back to boiler 21 through conduit 30, jacket 31 and conduits 32 and 33, the jacket 31 having a vent 31a to atmosphere.

The system operates at a partial vacuum and contains a solution of refrigerant in absorption liquid, such as, for example, a water solution of 40% lithium chloride by weight. When steam is supplied through conduit 20 to space 19, heat is supplied to tubes 16 whereby water vapor is expelled from solution. The absorption solution is raised by vapor-lift action with the expelled water vapor forming a central core within an upwardly rising annulus of the solution. The expelled water vapor rises more rapidly than the solution and the latter follows the inside walls of tubes 16. The water vapor flows upward through the tubes 16, vessel 18, conduit 34, vapor separating chamber 35 and conduit 36 into condenser 11 in which it is liquefied. The condensate formed in condenser 11 flows therefrom through a U-tube 37, flash chamber 38, and conduit 39 into evaporator 12.

The water supplied to evaporator 12 vaporizes therein to produce a refrigerating or cooling effect. The vapor formed in evaporator 12 passes through pipes 40 and 41 which are connected to absorber 14. To prevent disturbances in evaporator 12, the flash chamber 38 is provided to take care of any vapor flashing of liquid being fed to the evaporator through U-tube 37. The flashed vapor formed in the initial cooling of liquid flowing from the condenser passes through a conduit 42 to pipe 41 and mixes with the vapor formed in evaporator 12.

In absorber 14 refrigerant vapor is absorbed into concentrated absorption solution which enters through a conduit 43. The water vapor absorbed into solution dilutes the latter, and the diluted absorption solution flows through a conduit 44, a first passage in liquid heat exchanger

45, a conduit 46, vessel 47, and conduit 48 into the lower space 17 of generator 10. Water vapor is expelled out of solution in generator 10 by heating, and the solution is raised by vapor-lift action in the vertical tubes 16, as explained above.

The absorption solution in vessel 18 is concentrated since water vapor has been expelled therefrom in generator 10. This concentrated solution flows through a conduit 50, a second passage in liquid heat exchanger 45, and conduit 43 into absorber 14. This circulation of absorption solution results from the raising of liquid by vapor-lift action in vertical riser tubes 16, whereby the solution can flow to the absorber 14 and return from the absorber to the generator 10 by force of gravity.

The upper part of vessel 47 is connected by a conduit 51 to vessel 18, whereby the pressure in vessel 47 is equalized with the pressure in the upper part of generator 10 and condenser 11. Any liquid separated from vapor in separating chamber 35 flows through a U-trap 49 and conduit 51 back to vessel 47.

The lower part of evaporator 12 is connected by a conduit 52 and a jacket 53 to vertical tubes or riser 54, whereby unevaporated liquid flows from the evaporator and is preheated in jacket 53 by condensate flowing to boiler 21 through conduit 33. After being preheated in jacket 53, the unevaporated liquid passing from evaporator 12 is raised by vapor-lift action in risers 54 by the heating effect of the condensate in jacket 21, as described more fully in application Serial No. 350,882 of P. P. Anderson, Jr., filed August 3, 1940. The liquid is raised in risers 54 to a vessel 55 from which the liquid flows through a conduit 56 into absorber 14.

The heat liberated with absorption of water vapor in absorber 14 is transferred to a cooling medium which flows upward through a plurality of pipe coils 57. The cooling medium, such as water, for example, is supplied through a conduit 58 to a manifold 59 to which the lower ends of the pipe coils 57 are connected. The upper ends of the pipe coils are connected to a manifold 60 from which the cooling water flows through a conduit 61 to the condenser 11. The cooling water leaves condenser 11 through a conduit 62.

The system operates at a low pressure with the generator 10 and condenser 11 operating at one pressure and the evaporator 12 and absorber 14 operating at a lower pressure, the pressure differential being maintained by liquid columns. Thus, the liquid column formed in the tube 37 maintains the pressure differential between condenser 11 and evaporator 12. The liquid column in conduit 44 maintains the pressure differential between the outlet of absorber 14 and generator 10. The liquid column formed in conduit 43 and parts connected thereto including conduit 50 maintains the pressure differential between the inlet to absorber 14 and the upper part of generator 10. In operation, the liquid columns may form in conduits 43 and 50 and down-leg of tube 37 to the levels x, y and z, for example. The conduits are of such size that restriction to gas flow is effected without appreciably restricting flow of liquid. The liquid column formed in vessel 47 and conduit 48 provides the liquid reaction head for raising liquid in the vertical tubes 16 by vapor-lift action.

The vessel 47 is of sufficient volume to hold the liquid differential in the system and is of

such cross-sectional area that the liquid level therein does not appreciably vary, so that a substantially constant reaction head is provided for lifting liquid in generator 10. The vessel 31 is located below absorber 14 such a distance that, for the greatest pressure differential occurring between absorber 14 and the upper part of generator 10 during operation of the system, the liquid column formed in conduit 44 is below the lower end of absorber 14.

The evaporator 12 constitutes a cooling element of the refrigeration system and includes a plurality of tubes 63 to which cooling fins 64 are secured. The cooling element 12 may be arranged in a duct 65, indicated in dotted lines, forming part of a duct system connected to one or a plurality of enclosures and through which air is drawn in any suitable manner, as by a fan or blower, for example. As diagrammatically illustrated in the drawing, the cooling fins 64 are normal to the duct 65, but it should be understood that in practice the cooling fins 65 extend in the direction of the air flow and are parallel or lengthwise of the duct.

In the duct 65 is also disposed a heating element or radiator 66 comprising spaced headers 67 connected by a plurality of tubes 68 to which are secured heat dissipating fins 69. As in the cooling element 12 described above, the fins 69 in practice extend lengthwise of and are parallel to the duct 65, although in the drawing they are diagrammatically illustrated as being normal to the duct. The heating element 66 is supplied with steam through a conduit 70 from the boiler 21. The conduit 70 is connected to an upper part of one of the headers 67, and a suitable hand valve 71 is provided in the conduit for manually controlling the flow of steam to the heating element 66.

When it is desired to cool air flowing through conduit 65, the valve 71 is closed and valve 28 is opened, whereby steam produced in boiler 21 flows through conduit 20 to space 19 of generator 10. With heating of generator 10 a cooling effect is produced by cooling element 12, in the manner described above, and the cooling effect is transmitted to air flowing in duct 65. Conversely, when it is desired to heat air flowing through conduit 65, valve 28 is closed and valve 71 is opened, whereby steam flows from boiler 21 through conduit 70 to heating element 66. The heating effect produced by heating element 66 is transmitted to air flowing through the duct 65. The condensate formed in heating element or radiator 66 flows through a conduit 72 back to the boiler 21. A vent 73 is connected to conduit 72 at the region where the latter is connected to one of the headers 67, so that steam can flow from the heating element into the atmosphere.

In accordance with this invention, the vents 29 and 73 associated with the generator steam chamber 19 and heating element 66 are joined to provide a common vent, and when flow of steam takes place through the common vent the supply of fuel to burner 23 is reduced responsive to increase in temperature in the vent. As shown, the vents or vent conduits 29 and 73 are joined to a conduit 74 forming a common unobstructed vent which always permits steam to pass into the atmosphere either from heating element 66 or the generator steam chamber 19.

In the common vent is located a thermal bulb 75 which is connected by a capillary tube 76 to an expandable and contractible bellows 77 fixed at one end to a suitable support 78. The bellows 75

77, tube 76, and bulb 75 constitute an expandible fluid thermostat containing a suitable volatile fluid which increases and decreases in volume with corresponding changes in temperature. The bellows 77 expands and contracts with increase and decrease in volume of the volatile fluid, and these movements of the bellows 77 are utilized to control a switch 79 in an electrical circuit in which is connected the control device 25 in the fuel line to the burner 23.

As shown, the switch 79 is of the snap-acting type and includes upper and lower toggle arms 80 and 81 pivotally connected at their inner ends at 82 to a suitable support. A coil spring 83 is connected to the outer ends of toggle arms 80 and 81. The outer end of toggle arm 81 is connected by a link 84 to the free or movable end of bellows 77. The outer end of toggle arm 80 is provided with a contact 85 which moves between and is adapted to engage either one of two fixed contacts 86 and 87. The contact 86 is connected to a conductor 88 in which is provided an energizing coil 89 of an electrical relay 90.

The relay 90 includes a pivoted arm 91 to which is secured a contact 92 which cooperates with a fixed contact 93. The energizing coil 89 is adapted to attract arm 91 against the action of a spring 94 to close contacts 92 and 93. Arm 91 is connected to a dash pot 95 so that, when coil 89 is energized, the latter is effective to close contacts 92 and 93 after a definite time delay.

When arm 91 is raised to close contacts 92 and 93, a member 96 connected to the outer end of the arm is also raised to close the contacts of a relay 97 provided in a conductor 98 which is also secured to the pivoted arm 91. The conductor 98 is connected to conductor 88 at a region between the contact 86 and a manual switch 99 which is at one side of coil 89 of relay 90.

The contact 93 is connected through a coil 101 of a relay 102 to conductor 88. The contacts of relay 102 are connected in a conductor 103 which is connected at one end to contact 87 of switch 79, and at the opposite end to a terminal of a solenoid coil 104 in control device 25. The other terminal of coil 104 is connected by a conductor 105 to conductor 88, and to conductor 105 is secured a conductor 106. The inner end of toggle arm 80 is connected by a conductor 107 to conductor 98, the inner end of toggle arm 80 being insulated in any suitable manner from the pivotal connection at 82. The conductors 98 and 106 are connected to a suitable source of electrical supply.

The solenoid coil 104 of control device 25 is formed to receive a plunger 108 to which is fixed a valve 109. When solenoid coil 104 is energized, the plunger 108 is raised and valve 109 is in its open position to permit flow of fuel to burner 23. Conversely, when solenoid coil 104 is de-energized, the plunger 108 moves downward by gravity and valve 109 is moved to its closed position to shut off flow of fuel to burner 23. A small tube 110 is connected to conduit 24 and terminates in the vicinity of burner 23 to provide a pilot flame capable of lighting the burner when valve 109 moves to its open position to permit flow of fuel to the burner following a shut down period. A small coil spring 111 is provided in control device 25 to assist downward movement of plunger 108 and valve 109 by gravity when solenoid coil 104 is de-energized.

During normal operation of either the heating system or the refrigeration system, and when

no steam flows through the common vent conduit 74, the volume of the volatile fluid in the expansible fluid thermostat is reduced and the bellows 77 is in the contracted position shown in the drawing. In the contracted position of bellows 77, the contacts 85 and 87 are closed and the contacts of relay 102 are also closed. Under these conditions, solenoid coil 104 is energized and valve 109 is in its open position so that fuel flows to burner 23. From the source of electrical supply the completed circuit includes conductors 98 and 107, toggle arm 80, contacts 85 and 87, and conductor 103 to one terminal of solenoid coil 104. From the other terminal of solenoid coil 104 the circuit includes conductors 105 and 106 back to the source of electrical supply.

Let us now assume that the refrigeration system is being heated by steam from boiler 21 and flow of cooling water through conduit 58 stops, so that there is cessation of cooling water to absorber 14 and condenser 11. In such case the temperature of absorber 14 and condenser 11 will rise, and, as a result of the rise in temperature of these parts, the pressure and temperature of generator 10 and condenser 11 will also rise to an abnormally high value. Under these conditions heating vapor or steam supplied to chamber 19 flows through vent conduit 29 into the common vent 74 and thence passes into the atmosphere which constitutes an environment containing a gaseous fluid at a substantially constant pressure. When the temperature in vent conduit 74 rises, due to flow of steam therethrough, the volatile fluid of the expansible fluid thermostat increases in volume and causes the bellows 77 to expand. With expansion of bellows 77 clock-wise movement is imparted to lower toggle arm 81, and, when the coil spring 83 is moved past the straight line position of the toggle arms 80 and 81, the upper toggle arm 80 moves with a snap-action toward the left to separate contacts 85 and 87 and close contacts 85 and 86. When contacts 85 and 87 are separated to circuit described above for solenoid coil 104 is opened, whereby the latter is de-energized and valve 109 moves by gravity to its closed position to shut off flow of fuel to burner 23.

The closing of contacts 85 and 86 completes a circuit for energizing coil 89 of relay 90. From the source of supply this circuit includes conductors 98 and 107, toggle arm 80, contacts 85 and 86 to one terminal of coil 89. From the other terminal of coil 89 the circuit includes conductors 88, 105 and 106 back to the source of electrical supply. The dash pot 95 is provided so that a definite time delay must occur before arm 91 is raised sufficiently high to close contacts 92 and 93. In the event flow of cooling water is resumed through conduit 58 to pipe coils 57 of absorber 14 and to condenser 11 within the period of the time delay, the temperature of the absorber and condenser are reduced and the generator pressure and temperature will fall, whereby steam will no longer flow through vent conduits 29 and 74 and normal operation of the refrigeration system is resumed. With steam no longer flowing through vent conduit 74, the volatile fluid of the expansible fluid thermostat decreases in volume and causes the bellows 77 to contract. With contraction of bellows 77, counter-clockwise movement is imparted to lower toggle arm 81, and, when the coil spring 83 is moved past the straight line position of the toggle arms 80 and 81 in the opposite direction, the upper

toggle arm 80 moves toward the right with a snap-action to separate contacts 85 and 86 and close contacts 85 and 87. Since it has been assumed above that the switch 79 has been operated by the expansible fluid thermostat within the period of the time delay, the contacts 92 and 93 of relay 90 are still open and the contacts of relay 102 are closed, so that the circuit for solenoid coil 104 described above is again completed. With solenoid coil 104 energized again, valve 109 is moved to its open position whereby flow of fuel to burner 23 is resumed.

However, if the cooling water supply to absorber 14 and condenser 11 is not resumed within the period of the time delay effected by dashpot 95, and assuming that steam is still flowing through vent conduit 74 so that contacts 85 and 86 are closed and contacts 85 and 87 are open, the arm 91 of relay 90 is raised sufficiently high within the period of the time delay to close contacts 92 and 93. At the time the contacts 92 and 93 close, the contacts of relay 97 are also closed by member 96 which is raised by arm 91. This completes a holding circuit for energizing coil 89 of relay 90 in the event that toggle arm 80 of switch 79 is moved after the period of the time delay to open contacts 85 and 86. Thus, even though flow of steam through vent conduit 74 should stop after the period of the time delay and contacts 85 and 86 are separated in the manner described above due to cessation of steam flow, still a holding circuit is completed for energizing coil 89. This holding circuit from the source of electrical supply includes conductor 98 in which the contacts of relay 97 are closed by member 96, and switch 89 to one terminal of a coil 89. From the other terminal of coil 89 the holding circuit includes conductors 88, 105 and 106 back to the source of electrical supply. When the holding circuit for energizing coil 89 of relay 90 is completed, as just described, contacts 92 and 93 close to complete a circuit for coil 101 of relay 102, so that the contacts of this relay are open. This circuit from the source of supply includes the conductor 98 in which the contacts of relay 97 are closed by member 96, arm 91, contacts 92 and 93 of relay 90, and conductor 100 to one terminal of coil 101. From the other terminal of coil 101 the circuit includes conductors 105 and 106 back to the source of electrical supply.

When the contacts of relay 102 are closed after the definite time delay, the circuit for solenoid coil 104 cannot be completed even when the flow of steam stops through vent conduit 74 and the bellows 77 causes toggle arm 80 of switch 79 to move to the right in the manner described above to close contacts 85 and 87. After the definite time delay and with steam no longer flowing through vent conduit 74, so that contacts 85 and 87 are closed, the circuit for solenoid coil 104 can be completed by opening switch 99 to break the holding circuit for energizing coil 89 of relay 90. When the holding circuit for coil 89 is broken, contacts 92 and 93 separate and the contacts of relay 97 are opened. Separation of contacts 92 and 93 de-energizes coil 101, so that the contacts of relay 102 are closed and the circuit for solenoid coil 104 is again completed, assuming that there is no flow of steam through conduit 74 and contacts 85 and 87 are closed.

The single control just described takes the place of many controls that would otherwise be necessary to insure safe operation of the refrigeration system and also of the heating system.

The lithium chloride solution employed in the refrigeration system is of such concentration that it is near its solidifying point, and, in the event that blocking or plugging of the absorption liquid occurs in the absorption liquid circuit due to excessive salt precipitation, the temperature of the generator 10 will rise so that steam will pass through vent conduits 29 and 74 into the atmosphere. Also, during the periods when heating is being effected by heating element 66 there may be loss of air circulation in duct 65 due to operating failure of the blower or fan in the duct system. In such case, loss of load on the heating element 66 causes flow of steam through vent conduits 13 and 14. Thus, when any adverse operating condition causes steam to flow through vent conduit 14, the control illustrated will operate and function in the manner described above to reduce flow of fuel to burner 23.

In addition to the control described, a normal control is usually provided for controlling the fuel supply to the burner 23 or a plurality of such burners, whereby regulation of the steam supply to the heating element 66 or generator steam chamber 19 can be controlled. When the rate at which steam is supplied to chamber 19 is such that the latter is not completely filled with steam, air can enter the chamber with the result that self-regulation of the heating of generator 10 is effected which is proportional to the heat input to the boiler 21 by the burner 23. The normal control is generally operative responsive to a temperature condition affected by the heating or cooling elements, and may be of the character described in my application Serial No. 350,237, filed August 3, 1940, in which sequential control of a plurality of burners is effected.

The normal control may include switches which are also connected in the circuit or circuits of the solenoid coil or coils 104, and, when an adverse operating condition occurs which causes flow of steam through vent conduit 14, the control described above will open the circuits of the solenoid coil or coils to shut off flow of fuel to the burner or burners. When the adverse operating condition is corrected and steam no longer flows through vent conduit 14, the switch 79 closes the circuit for the solenoid coil or coils and the switch or switches associated with the normal control will exercise influence over the solenoid coil or coils 104 of the control devices 25, to regulate flow of fuel to one or a plurality of burners.

In Fig. 2 another embodiment of the invention is illustrated in which parts similar to those shown in Fig. 1 are designated by the same reference numerals. In Fig. 2 the control includes an expansible fluid thermostat like that in Fig. 1 having a bellows 77 fixed to a suitable support 18, a capillary tube 76, and a thermal bulb. The thermal bulb is not shown in Fig. 2, but it is to be understood that such a bulb is provided for the expansible fluid thermostat in Fig. 2 and is adapted to be located in the vent conduit 74. The bellows 77 is provided with a raised knob 112 opposite to which is a reset button 113. To the button 113 is secured a sleeve 114 which passes through an opening in a bracket 115 and is provided with an enlarged head 116 to receive a coil spring 117.

The switch 79' in Fig. 2 is like the switch 79 in Fig. 1 and includes upper and lower toggle arms 80' and 81', a coil spring 83' connected to the

outer ends of the toggle arms, and a pivotal connection at 82' to the bracket 115. The lower toggle arm 81' is not connected to knob 112 and is located in the path of movement thereof.

5 The upper toggle arm 81' is movable between a contact 87' and an insulated stop member 118, the contact 87' being adapted to cooperate with a contact 85' at the end of toggle arm 81'. Conductors 119 and 120 are connected to a source of electrical supply, the conductor 119 being connected to one terminal of solenoid coil 104 and the conductor 120 being connected to the inner end of toggle arm 80' which is insulated in any suitable manner from the pivotal connection at 82'. The contact 87' is connected by a conductor 121 to the opposite terminal of solenoid coil 104.

20 During normal operation of either the refrigeration system or the heating system, and when there is no flow of steam through vent conduit 34, the volume of the volatile fluid in the expansible fluid thermostat is reduced and the bellows 77 is in its contracted position. In such contracted position of bellows 77 the lower toggle arm 81' is bearing against the knob 112 and contacts 85' and 87' are closed to complete the circuit for the solenoid coil 104. This circuit from the source of electrical supply includes conductor 120, toggle arm 80', contacts 85' and 87', and conductor 121 to one terminal of solenoid coil 104. From the other terminal of coil 104 the circuit is completed through conductor 119 back to the source of electrical supply.

25 When an adverse operating condition occurs which causes flow of steam through vent conduit 14, the volume of the volatile fluid in the expansible fluid thermostat increases and causes expansion of bellows 77. With expansion of bellows 77 clockwise movement is imparted to lower toggle arm 81', and, when the coil spring 83' is moved past the straight line position of the toggle arms, both of the toggle arms move with a snap-action toward the left. With such snap-action the lower toggle arm 81' moves against the button 113, and the upper toggle arm 80' moves against the stop 118. When switch 79' is operated in the manner just described, contacts 85' and 87' are separated whereby the circuit for solenoid coil 104 is broken and the latter is deenergized. With de-energization of solenoid coil 104, the plunger 108 moves downward by gravity so that valve 109 is moved to its closed position to shut off flow of fuel to the burner.

30 In order to start flow of fuel to burner 23, it is necessary to push the enlarged head 116 against the action of spring 117 to move the button 113 toward the bellows 77. When this is done, counter-clockwise movement is imparted to lower toggle arm 81', and, when the coil spring 83' is moved past the straight line position of the toggle arms 35 in the opposite direction, the toggle arms move with a snap-action toward the right. With such snap-action movement, the lower toggle arm 81' bears against the knob 112 and the upper toggle arm 80' closes contacts 85' and 87'. The closing of contacts 85' and 87' completes the circuit for solenoid coil 104, whereby the latter is energized to cause valve 109 to move to its open position. The embodiment in Fig. 2 differs from that illustrated in Fig. 1 and described above in that, after the solenoid coil 104 is de-energized due to flow of steam through vent conduit 14, it becomes necessary to manually reset switch 79' by moving reset button 113.

35 The normal control switch for solenoid coil 104

may be connected in either of conductors 119 or 120 so that, when the switch 79' is closed, the normal control switch will exercise influence over the solenoid coil 104. As pointed out above, such normal control switch is usually operative responsive to a temperature condition affected either by the heating element 66 or the cooling element 12.

While several embodiments of the invention have been shown and described, it will be apparent that modifications and changes may be made without departing from the spirit and scope of the invention, as pointed out in the following claims.

What is claimed is:

1. In a refrigeration system operated by heat and having a heat receiving part provided with a chamber, a conduit connected to supply steam to said chamber from a source of supply, said chamber having a vent to atmosphere, and a device responsive to a condition affected by flow of steam through said vent from the chamber into the atmosphere for controlling flow of steam through said conduit.
  2. In refrigeration apparatus operated by heat and having a heat receiving part provided with a chamber, a boiler, a heater for heating said boiler to produce steam in the latter, said chamber being connected to receive steam from said boiler and having a vent to atmosphere, and means responsive to flow of steam through said vent from said chamber into the atmosphere for rendering said heater ineffective to heat said boiler.
  3. In a refrigeration system having a heat receiving part provided with a chamber, a conduit connected to said chamber for supplying steam thereto from a source of supply, said chamber having a vent to atmosphere, and a control device operative responsive to flow of steam through said vent from the said chamber into the atmosphere to reduce the flow of steam through said conduit to the chamber, said device being so constructed and arranged that, after cessation of flow of steam through said vent, the device must be manually operated to cause an increase in the flow of steam through said conduit to said chamber.
  4. In a refrigeration system having a heat receiving part provided with a chamber, a boiler, a heater for heating said boiler to produce steam in the latter, said chamber being connected to receive steam from said boiler and having a vent to atmosphere, whereby air can enter said chamber and self-regulation of said heat receiving part is effected which is proportional to the heat input to said boiler by said heater, and a thermostat having a part arranged to be heated by steam flowing through said vent from the chamber into the atmosphere for reducing the heat input to said boiler by said heater.
  5. In a refrigeration system having a heat receiving part provided with a chamber, a boiler, a heater for heating said boiler to produce steam in the latter, said chamber being connected to receive steam from said boiler and having a vent to atmosphere, and means responsive to increase in temperature resulting from flow of steam through said vent from said chamber into the atmosphere to reduce the heat input to said boiler by said heater, said last-mentioned means being so constructed and arranged that, when flow

- of steam through said vent stops within a definite period of time, the heat input to said boiler by said heater is automatically increased.
6. In a refrigeration system as set forth in claim 5 in which said last-mentioned means is ineffective to cause an increase in the heat input to the boiler by said heater after an interval of time longer than said definite period, even when flow of steam stops through said vent from said chamber into the atmosphere.
7. In a refrigeration system having a heat receiving part, a heating element associated with said part for heating the latter, said heating element being connected to receive steam from a source of supply, a vent to atmosphere connected to said heating element, and thermostatic means responsive to the flow of steam through said vent from within said heating element into the atmosphere for reducing the supply of steam to said heating element.
8. In a refrigeration system having a heat receiving part, a heating element associated with said part for heating the latter, said heating element being connected to receive steam from a source of supply, a vent to atmosphere connected to said heating element, and structure responsive to the flow of steam through said vent from within said heating element into the atmosphere for reducing the supply of steam to said heating element, such structure being so constructed and arranged that, when flow of steam through said vent stops within a definite period of time, the supply of steam to said heating element is automatically increased.
9. In a refrigeration system having a heat receiving part, a heating element associated with said part for heating the latter, said heating element being connected to receive steam from a source of supply, said heating element being unobstructedly vented to atmosphere so that steam can pass through the vent from the interior of said heating element to the atmosphere and air can enter the interior of said heating element when the supply of steam is insufficient to fill completely the interior of the heating element, and a control influenced by steam flowing through said vent from the interior of said heating element into the atmosphere for reducing the supply of steam to said heating element.
10. In a refrigeration system having a heat receiving part, a heating element associated with said part for heating the latter, said heating element being disposed in an environment containing gaseous fluid substantially at a constant pressure, means for supplying heating vapor to said heating element, said heating element being vented so that heating vapor may pass through said vent from the interior of said heating element into the surrounding environment and gaseous fluid may pass through said vent from the surrounding environment into the interior of said element when the rate at which heating vapor is supplied to said element is insufficient to fill completely the interior of the latter, and a control responsive to flow of heating vapor through said vent from the interior of said heating element to the surrounding environment for reducing the supply of heating vapor to said heating element.

ALBERT R. THOMAS.
